DESIGN FOR A SPOON OR SIMILAR ARTICLE

Grosvenor N. Allen, Charles A. Bennett, and Lloyd E. Ressegger, Oneida, N. Y., assignors to Oneida Limited, Oneida, N. Y., a corporation of New York

Application May 7, 1935, Serial No. 56,720

Term of patent 14 years

To all whom it may concern:

Be it known that we, Grosvenor N. Allen, Charles A. Bennett, and Lloyd E. Ressegger, residing at Oneida, county of Madison, State of New York, have invented a new, original, and ornamental Design for a Spoon or Similar Article, of which the following is a specification, reference being had to the accompanying drawing, forming a part thereof, in which,—

The essential feature of our new design is the ornamentation on the obverse side of the handle of the spoon.

We claim:

The ornamental design for a spoon or similar article as shown and described.

In testimony whereof we have hereunto set our hands.
